UNITED STATES PATENT OFFICE.

ALEXANDER W. FINLAYSON, OF DETROIT, MICHIGAN.

METHOD OF FORMING RADIATOR-TUBES.

1,304,551.

Specification of Letters Patent. Patented May 27, 1919.

Application filed October 8, 1917. Serial No. 195,369.

To all whom it may concern:

Be it known that I, ALEXANDER W. FINLAYSON, a citizen of the United States of America, residing at Detroit, in the county 5 of Wayne and State of Michigan, have invented certain new and useful Improvements in Methods of Forming Radiator-Tubes, of which the following is a specification, reference being had therein to the accompanying drawing.

The invention relates to the manufacture of radiator tubes and similar hollow articles from cast metal, and in which one or more baffle plates are cast in the structure. It 15 is the object of the invention to provide a method of supporting the baffle plates during the casting and also to hold them in fixed position after the casting is made. To this end the invention comprises the novel 20 method or process, as hereinafter set forth.

In the drawings:

Figure 1 is a longitudinal section through the radiator tube;

Fig. 2 is an elevation of the baffle-supporting tube with the baffles thereon;

Fig. 3 is a longitudinal section through a core having the baffles and their supporting tube embedded therein;

Fig. 4 is a section through the mold showing the cast radiator tube therein;

Fig. 5 is a section similar to Fig. 1 showing the manner of closing the perforations in the baffle-supporting tube; and

Fig. 6 is a horizontal section through the radiator tube.

The structure which is formed by my improved process comprises a hollow tubular member A having a series of enlargements B therein extending laterally therefrom. C' 40 is a central supporting member on which are mounted baffle-plates D, these being arranged within the enlargements B and serving to interrupt the direct passage through the tube and to compel a lateral circulation 45 around the baffle.

To form such an article it is necessary to provide a suitable core for forming the hollow tube and also to arrange the baffles in the core and to connect them with the supporting rod C'. This I accomplish by first 50 providing a tube C', preferably perforated, and having mounted thereon a series of baffle plates D in predetermined spaced relation to each other, as shown in Fig. 2. This 55 structure is then placed in a suitable core box and the core molded thereon, as shown

in Fig. 3, the core E covering both the baffles and the tube C' but leaving projecting portions C² of the baffles for anchoring in the casting. The core is then placed in an outer 60 mold F, as shown in Fig. 4, and the metal is cast therearound, embedding the projecting portions C² of the baffles and integrating therewith. During this operation the vapor generated by the heat of the metal on the 65 core will find access to the interior of the tube C', through the perforations G therein, and this tube will thus act as a vent for the core. After the casting is made the sand of the core is shaken out, leaving the baffles 70 D firmly anchored to the metal walls and the perforated tube C' supported by said baffles. The inner imperforate tube I having plugged ends is then telescopically engaged with the perforated tube C', thereby 75 closing the perforations and stopping communication through the tube C' from one side of the baffle to the other.

By forming the structure as described, the baffles are securely fastened and accurately 80 placed within the hollow tubes and are protected from the heat of the metal during the casting operation by being embedded in the core. The fact that the core is centrally vented throughout its length prevents the 85 entrapping of gases which might render the casting defective, and the subsequent placing of the imperforate tube within the perforated tube cuts off communication from one side to the other of the baffle.

What I claim as my invention is:

1. The method of forming a hollow casting having a baffle plate therein, comprising the mounting of the baffle plate upon a supporting rod, embedding said rod and 95 baffle plate in a core for forming the chamber within the hollow article, casting the article about said core so as to form an anchor for said rod and baffle, and removing the core, leaving the baffle supported 100 within the chamber.

2. The method of forming a hollow casting having baffles therein, comprising the mounting of a baffle upon a support, embedding the baffle and its support in a core fashioned to form the recess of said hollow body, casting the hollow body about said core with a portion engaging said baffle to anchor the same, and removing the core leaving the baffle supported within the recess.

3. The method of forming a hollow casting having baffles therein, comprising the

mounting of a baffle upon a perforated tubular support, embedding said baffle and support in a core fashioned to form the recess in the hollow body, casting the hollow body about 5 said core, the perforated tubular support forming a vent for the vapors generated and a portion of said casting anchoring said baffles, removing the core, and closing the perforations in said tubular support.

10 4. The method of forming a hollow casting with baffles therein, comprising the mounting of a baffle upon a perforated tubular support, embedding said baffle and support in a core fashioned to form the recess in the hollow casting, casting the body about said core, said perforated tubular support forming a vent for the vapors generated in the core and a portion of the casting 15 engaging said baffle to anchor the same, removing the core from the casting and tele-

20

scopically engaging an imperforate tube with said perforated tubular support to close said perforations.

5. The method of forming a radiator tube having a series of enlargements and baffles 25 therein, comprising the mounting of the baffles in predetermined spaced relation upon a perforated tubular support, embedding said baffles and support in a core fashioned to form the chamber within said tube, casting the tube about said core, said perforated tubular support constituting a vent for the gases generated in the core and a portion of the casting 30 engaging said baffles to anchor the same, removing the core, and telescopically engaging an imperforate tube within the perforated tubular member to close the perforations thereof.

In testimony whereof I affix my signature.
ALEXANDER W. FINLAYSON.
